UNITED STATES PATENT OFFICE.

JAMES E. MAYHEW, OF NEW YORK, N. Y.

POCKET INSTRUMENT.

Application filed January 2, 1926. Serial No. 78,788.

This invention relates to pocket instruments and particularly to those of the type which are adapted to serve in performing a number of different operations. Draftsmen, engineers, and many other persons often require the services of such instruments, as for example a rule, calipers or compass at times when it is extremely inconvenient to carry individual instruments 10 of this kind in the pocket.

The object of the present invention is to provide an instrument of this character of improved construction which will not only, in many instances, serve in place of these 15 three individual instruments, but will also perform other functions. Thus the pocket instrument of the present invention will serve as a square for measuring a right angle, as an envelope opener, a pencil sharpener, a 20 cord cutter, a scorer, and a wire or drill gauge. The improved construction of the instrument renders it compact so that it may be carried in the pocket without inconvenience; moreover, the construction is such as 25 to render it particularly strong so that it is capable of successfully carrying out its intended functions, and the improved structure enables these functions to be performed conveniently and satisfactorily.

30 The improved instrument or tool of the invention in general comprises a pair of cooperating relatively thin flat plates, each of these plates having a longitudinally extending tubular portion between the longitudinal 35 edges thereof. These tubular portions of the two plates are telescoped one within the other thus bringing one of the plates into superposed relation to the other and securing them in slidable relation one to the other. 40 The two plates thus have two pairs of cooperating marginal portions. A pencil may be inserted within the interior of the telescoped tubular portions and, as a pocket clip is provided on the outer tubular portion, both 45 the instrument and pencil may be conveniently and safely carried.

The invention will be better understood in its various aspects by referring to the accompanying drawings which show by way of example a form of pocket instrument constructed in accordance with the principles of the present invention. In these drawings:

50 Fig. 1 is a perspective view of the parts of the instrument in telescoped relation and mounted upon a pencil;

55 Fig. 2 is a plan view of the upper and low-

er cooperating plates with their tubular members in telescoped relation;

Fig. 3 is a transverse sectional view taken 60 on line 3—3 of Fig. 2;

Fig. 4 is a front view of the parts of the instrument assembled as in Fig. 2;

Figs. 5 and 6 illustrate respectively the 65 separate lower and upper cooperating plates;

Fig. 7 illustrates the use of the instrument 65 as a pencil sharpener;

Figs. 8, 9 and 10 are detailed views showing the mounting of the knife; and

Figs. 11 and 12 show the instrument in use 70 as an inside caliper.

Referring now to these drawings, the improved instrument of the invention comprises upper and lower cooperating plates or members 20 and 21 respectively, each of 75 said plates having flat marginal portions 22 separated by longitudinally extending tubular portions and being made of metal or any suitable material. Thus the upper member 30 (Fig. 6) has a front marginal portion 22 and a rear marginal portion 23, these 80 two portions lying flat in substantially the same plane and being separated by a tubular portion 24 which extends longitudinally throughout nearly the whole length of the member. Similarly, lower cooperating member 21 comprises a front marginal portion 25, a rear marginal portion 26 and a longitudinal tubular portion 27.

The tubular portion 24 of the upper member 20 is slightly larger than the tubular 90 portion 27 of the lower member 21 and is adapted to fit snugly over the outside of portion 27 so that these two tubular portions 95 may be telescoped the one within the other as may be seen in Figs. 1, 2, 3, 4 and 7. When the parts are thus telescoped, the marginal portions 22 and 23 of the upper member 20 are held in flat superposed relation 100 upon the flat marginal portions 25 and 26 of the lower member 21.

The scale 28 in inches, centimeters or other desired unit, is laid off upon the rear marginal portion 23 of the upper slidable member 20 and a similar scale 29 is laid off 105 on the rear marginal portion 26 of the lower slidable member 21, these two scales 28 and 29 being arranged complementary to one another so that when the member 20 is slid to the right of member 21 as viewed in Fig. 2, the digits on these two scales will add, 110 thus providing an extension rule twice the length of the respective scales 28 and 29.

and consequently of substantially twice the length of coaxing slidable members 20 and 21. By reason of the cooperating tubular structure which maintains the coaxing marginal portions 22 and 23, and 23 and 26 in contact with one another the rule is relatively rigid even when well extended and the two scales 28 and 29 thus kept in alignment with one another.

10 Along the center line of the tubular portion 27 of the lower member 21 there is a series of accurately formed holes 30 of varying diameters corresponding to the sizes of some standard gauge system and by sliding 15 the member 20 either toward the right or left of member 21 as viewed in Fig. 2 a plurality of these holes are exposed whereby they may be used as a wire and drill gauge.

16 In order to provide for the use of the improved instrument as a caliper device it is provided with a pair of caliper fingers 31 and 32 attached respectively at one end of the slidable members 20 and 21. The caliper finger 31 is mounted upon an extension 33 of the front marginal portion 22 which carries the finger 31 slightly beyond one end of the tubular portion 24. The finger 32 is spaced a corresponding distance from the end of tubular portion 27 of member 21 and is attached to member 21 by means of an extension 34 of the rear marginal portion 26 of member 21.

17 The right hand lateral edge 35 of finger 31 is made straight as is also the left hand lateral edge 36 of finger 32. The opposite edges of these two fingers are curved for purposes which will appear later. By sliding the upper member 20 to the left as is shown in the dotted position of Fig. 2 the finger 31 is carried to the left of finger 32 and the parallel straight edges 35 and 36 may be used for the purpose of caliper any object which it is desired to place between these edges. Such a dimension A for example, as shown in Fig. 2 is then read by means of a scale 37 laid off in preferably finely divided units along the upper edge of front marginal portion 22.

18 When members 20 and 21 exactly overlie one another so that the ends register, or when member 20 is slid to the right of member 21 the straight edge 35 of caliper finger 31 is to the right of straight edge 36 of caliper finger 32 and hence these edges may be used as an inside caliper to measure the diameter for instance of an aperture. In order to use the device as an inside caliper it is necessary to provide two scales which are shown in Figs. 11 and 12. In Fig. 11 the diameter of the aperture 38 which it is desired to measure is smaller than the width of the fingers 31 and 32 but inasmuch as these fingers are made each with one rounded edge as referred to above, the hole may be caliper without difficulty and the diameter of

the hole 38 is read on a short scale 39 on the right hand front edge of marginal portion 25 which is exposed by the sliding of member 20 slightly to the left to bring the edges 35 and 36 into contact with the surface of hole 38. The length of scale 39 needs only to be equal to the width of fingers 35 or 36.

19 When apertures larger than the width of fingers 35 or 36 are to be caliper it is necessary to slide member 20 to the right of member 21 and the dimensions of such apertures are read by reversing the instrument so as to bring to view a scale 40 upon the back of marginal portion 23 of member 20, this scale being exposed by the sliding of the plates one upon the other. The dimension of the aperture is indicated by the distance of the right hand end 41 of member 21 from the right hand end 42 of member 20 as viewed in Fig. 2. The numbers on this scale 45 commence where the numbers on scale 39 leave off. In other words, if the highest number on scale 39 is $1/4$ ", scale 40 commences with $1/4$ ".

20 The tips of fingers 31 and 32 are nicely ground so as to relieve the extreme sharpness to prevent them from catching in the pocket, and the tip of finger 32 serves admirably for scoring paper or other material when it is desirable to weaken it to facilitate bending.

21 The lower member 21 is provided with a stylus hole 42 about the center lengthwise of finger 32, and with a series of pencil holes 43 along the marginal portion 25, each of the holes of this series being provided with markings to indicate their respective distance from the stylus hole 42. By placing a stylus through the aperture 42 and a pencil in one of the apertures 43 the instrument is used as a compass to draw circular lines. The upper member 20 has a longitudinal slot 44 in the marginal portion 22 thereof for the purpose of exposing the series of holes 43 so that it is not necessary to separate the members 20 and 21 in order to use the instrument as a compass unless it is desired to do so. To facilitate its use without separating the members a second series of markings for the holes 43 is placed along the upper surface of marginal portion 22 as indicated by the reference numeral 45. By bringing the right hand ends of members 20 and 21 into alignment the markings 45 will register with their respective holes 43 which are viewed through the slot 44.

22 The straight edge 36 of finger 32 is cut at a right angle with the straight edge of marginal portion 26 so that the corner formed by these two meeting edges may be used as a square. Moreover, scales 46 and 47 are laid off in fine subdivisions from the corner of this square, one of these along edge 36 and the other along the edge of portion 26. The scale 46 may be used for measuring

short distances in relatively inaccessible places by inserting the instrument endwise into the inaccessible place.

It was stated above that finger 32 of member 21 was attached thereto by an extension 34. This extension holds the finger in spaced relation to the remainder of the member 21, a slot 47 of about the same width as the finger 32 extending laterally from the 10 front edge of member 21. At the bottom of this slot 47 there is a knife edge by means of which the instrument may be conveniently used for sharpening pencils as is shown in Fig. 7. This knife edge may be formed 15 merely by sharpening the bottom of slot 47, or it may comprise a small rectangular piece of hardened steel 48 with a single sharpened edge as shown in Fig. 10 and held in place as is shown in Figs. 8 and 9.

20 Referring particularly to Fig. 9 in cutting the slot 47 a tongue 49 of appropriate length to fold around the knife 48 is left projecting from the bottom of the slot. A rectangular aperture 50 is punched in symmetrical relation to the line which is to 25 form the bottom of the slot through which the sharpened edge of the knife protrudes after the knife is secured in place. The tongue 49 is first bent along dotted line 51 30 around the rear edge of the knife, and then both the knife and the bent tongue are folded along the line forming the bottom of the slot into the position shown in Fig. 8 with the sharpened edge of the knife protruding 35 through the aperture 50. This mounting firmly holds the knife in position and the knife may be used as a cord cutter or a 40 pencil sharpener.

Inasmuch as the knife edge or blade 48 is disposed adjacent the base of the transversely projecting caliper finger 32, finger 32 forms a sort of guard for preventing the blade from catching in the pocket. Moreover, the front marginal portion 22 of member 20 which extends to the left beyond the tubular portion 24 is arranged to lie directly in front of the knife edge and completely protects the fingers or hands of the manipulator from coming in contact with 50 the knife.

The outer edge of slot 47 which is the inner edge of finger 32 is shaped to curve gradually out to the tip of finger 32 and finger 32 thus constitutes a slitter blade with a caliper finger at its outer end. This slitter blade is useful in opening envelopes and for like purposes.

The members 20 and 21 comprising the improved pocket instrument are telescoped together by means of their tubular portions 24 and 27 and mounted upon a pencil 52 by inserting the pencil through the tubular member 27 as is to be seen in Fig. 1. The outer tubular member 24 has a spring clip 53 preferably formed integrally therewith

by which both the instrument and the pencil are conveniently carried in the vest pocket.

Because of the improved construction of the instrument of the present invention, the 70 marginal portions carrying the respective scales are held flat against one another in effective cooperative relation. Furthermore, the compactness of the device renders it unobjectionable to carrying in the pocket. 75

I claim:

1. A device of the character described comprising a pair of cooperating members each having marginal portions separated by a longitudinally extending tubular portion, 80 said tubular portions being telescoped one within the other so as to secure said members in slidable relation with the marginal portion of one member superposed upon those of the other, similar scales being provided along one pair of superposed marginal portions to provide an extension rule, said device having a stylus aperture and a pencil aperture whereby it may serve as a 85 compass. 90

2. A device of the character described comprising a pair of cooperating members each having marginal portions separated by a longitudinally extending tubular portion, 95 said tubular portions being telescoped one within the other so as to secure said members in slidable relation with the marginal portions of one member superposed upon those of the other, similar scales being provided along one pair of superposed marginal portions to provide an extension rule, one 100 of said cooperating members having a stylus aperture near one end thereof and a series of pencil apertures along one marginal portion, 105 each of these apertures being marked to indicate its distance from the stylus aperture.

3. A device of the character described comprising a pair of cooperating members each having marginal portions separated by a longitudinally extending tubular portion, 110 said tubular portions being telescoped one within the other so as to secure said members in slidable relation with the marginal portions of one member superposed upon those of the other, similar scales being provided along one pair of superposed marginal portions to provide an extension rule, one of said cooperating members having a stylus aperture near one end thereof and a series of pencil apertures along one marginal portion, 115 each of these apertures being marked to indicate its distance from the stylus aperture, and the coacting marginal portion of the upper cooperating member having a longitudinal slit for exposing 120 said series of pencil apertures.

4. A device of the character described comprising a pair of cooperating members each having marginal portions separated by a longitudinally extending tubular por. 130

tion, said tubular portions being telescoped one within the other so as to secure said members in slidable relation one to the other with the marginal portions of one member superposed upon those of the other, and a caliper finger projecting laterally from a marginal portion of each of said members.

5. A device of the character described
10 comprising a pair of cooperating members secured in longitudinally slidable relation one to the other and each provided with a laterally projecting caliper finger, said members being slidable to bring said fingers into one relative position to serve as outside calipers and into a second relative position 40 to serve as inside calipers and scales being provided upon said members for indicating the spacing of said fingers in both of said positions, the scale for indicating the spacing of said fingers when in said second 45 position being in two sections, one section being on one side of one of said cooperating members and the other section being on the opposite side of the other member.

6. A device of the character described comprising a pair of cooperating members 20 each having marginal portions separated by a longitudinally extending tubular portion, said tubular portions being telescoped one within the other so as to secure said members in slidable relation one to the other with the marginal portions of one member superposed upon those of the other, one marginal portion of one of said members extending longitudinally beyond the tubular portion thereof and carrying at its end a 30 caliper finger extending laterally across the end of the member, and a cooperating caliper finger on the other of said members.

7. A device of the character described

comprising a pair of cooperating members secured in longitudinally slidable relation 35 one to the other and each provided with a laterally projecting caliper finger, said members being slidable to bring said fingers into one relative position to serve as outside calipers and into a second relative position 40 to serve as inside calipers and scales being provided upon said members for indicating the spacing of said fingers in both of said positions, the scale for indicating the spacing of said fingers when in said second 45 position being in two sections, one section being on one side of one of said cooperating members and the other section being on the opposite side of the other member.

8. A device of the character described 50 comprising a pair of cooperating members each having marginal portions separated by a longitudinally extending tubular portion, one of said members having a series of apertures of varying size along the center of the tubular portion thereof to serve as a wire gauge, said tubular portions being telescoped one within the other so as to secure said members in slidable relation one to the other with the marginal portions of one 55 member superposed upon those of the other, said series of holes of varying size being concealed when the tubular portions are in telescoped relation.

In testimony whereof I affix my signature.
JAS. E. MAYHEW.
